UNITED STATES PATENT OFFICE.

PETER BROADBOOKS, OF BATAVIA, NEW YORK.

PLIERS.

SPECIFICATION forming part of Letters Patent No. 792,962, dated June 20, 1905.

Application filed June 22, 1904. Serial No. 213,588.

To all whom it may concern:

Be it known that I, PETER BROADBOOKS, a citizen of the United States, residing at Batavia, county of Genesee, and State of New York, 5 have invented a certain new and useful Improvement in Pliers, of which the following is a specification.

My invention relates to a new and useful improvement in pliers, and has for its object 10 to improve upon pliers in several ways, so as to give to them greater strength and better efficiency without adding any complication thereto.

Some of the objects are as follows: That 15 portion of the pliers in which the levers cross one another is formed circular in the ordinary manner, and these circular portions have the ordinary notches formed in the sides thereof, which notches are adapted to cross one another when the pliers are closed to form a 20 wire-cutter. One of my improvements consists in making one of these notches wider than the other notch, and thus the same exactness is not required in bringing them in 25 alinement as where the notches are the same size.

Another improvement in my invention is 30 providing a groove formed in the outside pivotal portion of one of the levers, which, coacting with the other jaw, forms a wire-cutter in which the wire may be cut while it is held parallel with the pliers. By this construction I gain strength in the jaws of the lever, as 35 only one beveled notch is required in one lever to accomplish this result. This will leave the full strength right where the greatest strength is required.

Another object of my invention is obtained 40 by providing a set-screw to limit the movement of the levers and to allow for both cutting-notches to be in alinement when the levers are spread. The set-screw also serves in holding the levers together.

A further object of my invention is to attach side plates to a pliers of this description, 45 said side plates so attached to the levers and jaws as to provide a parallel movement and provide a shear and cutting-nipper with but small additional expense.

Other objects will be enumerated in the 50 body of the specification.

With these ends in view this invention consists in the details of construction and combination of elements hereinafter set forth and then specifically designated by the claims. 55

In order that those skilled in the art to which this invention appertains may understand how to make and use the same, the construction and operation will now be described in detail, referring to the accompanying drawings, forming a part of this specification, in which—

Figure 1 is an elevation of one side of my improved pliers; Fig. 2, a similar view to Fig. 1, showing the pliers open; Fig. 3, an elevation of the opposite side of the pliers when closed; Fig. 4, an edge elevation of the pliers; Fig. 5, a side elevation of the pliers, showing a modified form of construction. 65

A and B represent the two levers, which 70 have formed therewith the circular pivotal portions A' and B', respectively. These pivotal portions are cut away so as to be just half of the thickness of the levers and jaws, so that the pliers will be flush upon each side. These 75 pivotal portions are pivoted together by means of the rivet or screw C, and D represents the jaws of the pliers formed integral with the levers.

E and E' are notches formed in the periphery of the pivotal portions A' and B'. The notch E is formed considerably wider than the notch E', and the cutting edge is formed upon the lower edge of the notch E, and when the levers are spread this cutting edge is lower 85 than the lower edge of the notch E', thus producing the advantages above referred to. 80

F is a beveled groove formed upon the outside of the pivotal portion A' of the lever A. This groove commences at the surface near 90 the center of the pivotal portion and is beveled downward to the periphery of said pivotal portion, and when the levers are spread a wire may be placed in this groove F, and when the levers are closed the opposite jaw 95 will act as a cutter to shear off the wire.

B² is a groove formed in the periphery of the pivotal portion B'.

G is a screw threaded through the upper portion of the lever A, the end of said screw adapted to enter the groove B². This groove B² is of such a length as to limit the opening 5 of the pliers to bring the notches E and E' in proper alinement as well as the beveled groove F.

H is a plate secured to one of the jaws at the point H' and H², so as to move with said 10 jaw. This plate H is provided with a cutting edge H³, formed radial with the point H². I is a plate arranged upon the same side of the plier as the plate H and pivoted to the same jaw at the point H². The pivotal portion 15 of the plate H fits in a circular recess in the plate I, so that the plates will be flush. The plate I is formed with a cutting edge I', opposed to the cutting edge H³ and also extending radial from the pivotal point H². J 20 is a stud swiveled in the lever opposite the lever of the jaw to which the plates are attached, and the lower end of the plate I extends through the stud J and adapted to slide therein as the levers are opened and closed. In 25 Fig. 1 I have shown the levers closed and in Fig. 2 opened. It will thus be seen that in this manner I provide a side cutter on which great strength can be exerted on account of the compound leverage thus employed. If 30 desired, a horn or hook K may be attached to the upper end of the plate I and used as a bail-hook for pulling staples, &c.

In Fig. 5 I have shown a modified construction in which a side plate L is pivoted at the 35 points L' to each of the jaws, the lower end of said plates sliding through studs M, attached to levers opposite the jaws to which the plates are pivoted. Thus as the levers are opened and closed the plates will be caused to move parallel with one another, and thus provide a 40 shear and cutting-nipper with but small additional expense.

Of course I do not wish to be limited to the exact construction here shown, as slight modifications could be made without departing from the spirit of my invention.

Having thus fully described my invention, what I claim as new and useful is—

1. In a pair of pliers of the character described, two levers led together and pivoted, the pivotal portion of each lever being circular, plier-jaws formed with each lever upon the opposite side of the pivotal portion, a notch formed in the periphery of each circular pivotal portion, the notch in one portion being wider than the notch in the other portion, a slot formed in the periphery of the pivotal portion of one lever, a screw threaded through the other lever and entering said slot for the 50 purpose of limiting the spreading of the levers, as specified.

2. In a pair of pliers, two levers, each lever having a jaw formed therewith, said levers crossing one another and being pivoted together, the portions surrounding the pivot of each lever being circular, a notch provided in the periphery of each circular portion, one notch adapted to pass the other when the levers are closed, one notch being wider than the notch in the other portion, the periphery of one circular pivotal portion being provided with a slot, a set-screw threaded through one of the levers and entering said slot, a radial groove formed in the outside of one of the pivotal portions, said groove commencing at the surface of the pivotal portion near the center thereof and extending at an incline into the pivotal portion toward the periphery, the jaw formed with the opposite pivotal portion adapted to cross the outer end of said groove 80 when the jaws are closed, as and for the purpose specified.

3. In a pair of pliers of the character described, two levers, each having a jaw formed therewith, said levers crossing one another and being pivoted together, a side plate pivoted to one of the jaws, a stud swiveled in the lever formed with the opposite jaw, the lower end of said plate passing downward through said stud and adapted to slide therein as the 85 jaws are opened and closed, a cutting edge formed upon the outer edge of said plate radial with the pivotal point of said plate and jaw, a second plate secured rigidly to the same jaw as the other plate, a cutting edge formed 90 with said last-named plate opposed to the other cutting edge and also formed radial with the pivotal point of the first-named plate and jaw, as specified.

4. In a pair of pliers of the character described, two cross-levers pivoted together, jaws formed with each lever, a side plate arranged upon one side of the pliers, said side plate pivoted to one of the jaws, a stud swiveled in the lever formed with the opposite jaw, the lower end of said plate passing through said stud and adapted to slide therein, a cutting edge formed with said plate radial with the pivotal point, a plate formed with the same jaw as the other plate is pivoted to, said plate 100 also provided with a cutting edge radial with the pivotal point of the first-named plate, and a horn or hook extending outward and curved downward from the upper end of the first-named plate, as and for the purpose specified. 105

In testimony whereof I have hereunto affixed my signature in the presence of two subscribing witnesses.

PETER BROADBOOKS.
